UNITED STATES PATENT OFFICE

171,522

GASKET CUTTER BLADE

Charles H. Zimmerman, Norwood, Ohio, assignor
to Zimmerman Packing Company, Norwood,
Ohio, a corporation of Ohio

Application December 16, 1949, Serial No. 6,677

Term of patent 14 years

(Cl. D22—3)

To all whom it may concern:

Be it known that I, Charles H. Zimmerman, a citizen of the United States, residing at Norwood, in the county of Hamilton and State of Ohio, have invented a new, original, and ornamental Design for a Gasket Cutter Blade, of which the following is a specification, reference being had to the accompanying drawing, forming part thereof.

Fig. 1 is a side elevational view of a gasket cutter blade, showing my new design, and

Fig. 2 is an edge elevational view of the gasket cutter blade, shown in Fig. 1.

I claim:

The ornamental design for a gasket cutter blade, substantially as shown.

CHARLES H. ZIMMERMAN.
